[57] CLAIM

The ornamental design for an automatic pot stirrer, as shown and described.

DESCRIPTION

FIG. 1 is a perspective view of an automatic pot stirrer showing my new design;

FIG. 2 is a perspective view thereof, shown without the environmental structure;

FIG. 3 is a left side elevational view thereof, the right side, front and rear being the same as this view;

FIG. 4 is a top plan view thereof; and,

FIG. 5 is a bottom plan view thereof.

The broken line illustration shows environmental structure and forms no part of the claimed invention. Undisclosed surfaces are plain and unornamented.
